Attorney

UNITED STATES PATENT OFFICE.

WILHELM MAUSS, OF JOHANNESBURG, TRANSVAAL, SOUTH AFRICA.

CENTRIFUGAL APPARATUS WITH PLANETARY MOVEMENT.

1,339,272.

Specification of Letters Patent.

Patented May 4, 1920.

Application filed September 4, 1919. Serial No. 321,708.

To all whom it may concern:

Be it known that I, WILHELM MAUSS, subject of the King of Great Britain, residing at Cullinan Buildings, Main and Simmonds 5 streets, Johannesburg, Transvaal Province of the Union of South Africa, have invented certain new and useful Improvements in Centrifugal Apparatus with Planetary Movement, of which the following is a 10 specification.

The present invention has reference to centrifugal apparatus of the kind in which two or more bodies such as separating drums are rotated at high speed about a 15 central axis and are also rotated at a relatively slow rate about their individual axes.

In such apparatus the unbalanced centrifugal tendency of each of the bodies due to its rotation about the central axis causes excessive wear of the bearings in which they 20 rotate and of the gear wheels by which they are rotated. It is the object of the present invention to overcome this difficulty.

In the accompanying drawings Figure I 25 is an elevation, partly sectioned, of a planetary separator with two drums; Fig. II is a plan of the same also partly sectioned. Fig. III is a diagram illustrating the operation.

1 is a shaft which is rotated at high speed and carries the drum housing. Said housing comprises an upper plate 2, a lower plate 3, two arcuate drum seatings 4, and side ties 5. Bolts 6 passing through the 35 upper and lower plates 2, 3, and the drum seatings 4, secure said parts together. The drums 7 are cylindrical vessels supported on flanges 8 formed on the seatings 4, and they bear outwardly against said seatings 4.

40 The shaft, drum housing and drums rotate as a whole about a central axis 9, as indicated by the arrow A, Fig. II. The individual drums are also rotated about their own axes 10 as indicated by the arrows B.

45 The mixture to be treated is fed into the drums from the hopper 11 and segregates in the part 12 of the drum remote from the main axis 9. The liquid flows away over the inwardly directed lip 13, while the separated solid is carried by the individual rotation of the drum near to the main axis 9, where it is parted from the drum and passes out through the discharge apertures 14.

50 The centrifugal tendency of each drum

causes it to press heavily on its seating 4 and consequently to offer great resistance to rotation on any such relatively fixed part.

According to the present invention, the 60 drum is intermittently retracted from its seating and while off its seating is rotated by bodily movement with it of the means by which it is retracted.

15, 15 indicate straps which pass about the 65 periphery of the drums remote from the main axis 9. To each end of each strap a link 16 is pivoted by a pin 17; and the links of the pair on each side are pivoted by pins 18 to the strap 19 of an eccentric sheave 70 20. The straps 15, the links 16 and the straps 19 thus form an endless loop or chain. The length of said chain can be regulated by adjusting screws 21.

The eccentrics 20 are fast with gear wheels 75 22 revolvably mounted on the housing and revolved by rolling about a central pinion 23. Said pinion 23 is mounted in bearings in the drum housing and is prevented from turning by an arm 24 fast with it. Said arm 80 engages a fixed part such as the pin 25 projecting from a collar 26 rotatably mounted on the pinion shaft 27, to which collar are attached the ends of spring arms 28 coupled at their outer ends to fixtures. Said arms 85 28 not only prevent the collar 26 from turning but also control gyration of the machine as a whole.

In Fig. III the circles 29 indicate the loci of the pins 18 connecting the link 16 90 to the eccentric straps 19. The arcs 30 indicate the loci of the pins 17 connecting the links 16 to the straps 15, while the straight lines 31 are the loci of the centers of the arcs of the straps 15, and also in 95 part the loci of the axes 10 of the drums 7. Four principal positions of the parts are shown respectively by full thick lines, full thin lines, dotted lines and chain dotted lines; the corresponding positions of the 100 links 17 and 18 and centers of the arcs 15 being indicated in the first position by the letters C, in the second position by the letters D, in the third position by the letters E and in the fourth position by the letters F.

The circles 29 are substantially tangential to a tangent (i. e. 31¹), between the arcs 30. As the result the maximum effective length of the chain system, or in other 110 words, the greatest separation of the straps

15 is attained at position D, when the links 15 and the eccentric straps 16 are alined. From D onward, the effective length decreases to a minimum at position F, and it increases again during the movement from F to D. Referring to the loci 31, the centers of the arcs 15 reciprocate between the outer extreme positions D and the inner extreme positions F. From position C to position 10 E the chain is circulated clockwise, while from position E to position C the circulation is reversed or anti-clockwise.

The combined effect of this virtual lengthening and shortening of the chain and its 15 reciprocatory circulating movement is utilized as follows.

The length of the chain is so regulated by the adjustment 18 that the straps pick up the drums 7 at about position E. At this 20 position the circulating movement is neutral and the drums merely begin to lift from their seats 4. From E to C the drums remain lifted and are also rotated counter-clockwise by the circulation of the chain.

25 At point C the circulatory motion has ceased and the drums are thus deposited on their seats without rotational movement. From C to E the straps clear the drums and are circulated clockwise, whereby they 30 are restored to position for the next movement of the drums.

While Fig. III shows relatively large movement of the parts, it is only necessary in practice to lift the drums, say one sixteenth of an inch, and the circulatory movement is correspondingly small. The movements are, however, repeated frequently and produce the effect of a continuous slow rotation of the drums in one direction.

40 Owing both to the small individual movements of the drums and the toggle action of the eccentrics on the chain, the force exerted by the eccentrics can be kept within reasonable limits even with exceedingly heavy centrifugal forces exerted by the drums. Similarly the energy consumption is small; a substantial proportion of the energy expended in retracting and rotating the drums is recovered in the reverse movement of restoring them to their seats and arresting 50 their rotation.

I claim:

1. In centrifugal apparatus, a number of bodies having planetary movement, seatings 55 for the bodies opposing their centrifugal movement, an endless flexible loop embracing said bodies, means to deform the loop periodically to retract said bodies from their seatings for rotation, and to circulate the loop while the bodies are so retracted.

2. In centrifugal apparatus, a number of bodies having planetary movement, seatings for the bodies opposing their centrifugal movement, an endless flexible loop embracing 60 said bodies, and means periodically to

deform the loop to retract said bodies from their seatings, said means also circulating the loop.

3. In centrifugal apparatus, a number of bodies having planetary movement, seatings 70 for the bodies opposing their centrifugal movement, an endless flexible loop embracing said bodies, and means operating at a point of the loop between the bodies to move said point with a rotary motion whereby the 75 loop is periodically virtually shortened and also circulated.

4. In centrifugal apparatus, a number of bodies having planetary movement, seatings 80 for the bodies opposing their centrifugal movement, an endless flexible loop embracing said bodies, and providing a portion extending between the bodies, and means for moving a point in said portion in a circle having a common tangent with the bodies. 85

5. In centrifugal apparatus, a number of bodies having planetary movement, seatings 90 for the bodies opposing their centrifugal movement, straps adapted to embrace said bodies remotely from the center of rotation, links connected to said straps and mechanism moving the ends of said links with a circular movement tangential to their alined position.

6. In a centrifugal apparatus, a number 95 of bodies having planetary movement, seatings for the bodies opposing their centrifugal movement, straps adapted to embrace said bodies remotely from the center of rotation, rotatable eccentric sheaves, straps on 100 said eccentrics and links connecting said body straps to eccentric straps.

7. In centrifugal apparatus, a number of bodies having planetary movement, seatings for the bodies opposing their centrifugal 105 movement, an endless loop comprising straps adapted to embrace the bodies, links and eccentric straps, rotatable eccentric sheaves actuating said eccentric straps, the rotation of the eccentric sheaves alternately loosing 110 the body straps from the bodies and tightening the same to retract the bodies from their seats, said rotation also circulating the loop in one direction while the bodies are thus retracted and circulating the loop in the 115 other direction when the body straps are loose.

8. In centrifugal apparatus, a number of bodies having planetary movement, seatings for the bodies opposing their centrifugal 120 movement, an endless flexible loop embracing said bodies, means periodically to deform the loop whereby it is alternately contracted to retract the bodies from the seatings and enlarged to clear the bodies, said 125 means also circulating the loop to start the bodies to rotate from rest at about the beginning of the retraction and to stop their rotation as the strap clears them.

9. In centrifugal apparatus, a rotatable 130

housing, bodies rotatably carried in said housing symmetrically about the axis of rotation thereof, seatings for said bodies in the housing, a separate strap adapted to embrace the outer part of each body, eccentric sheaves rotatably mounted in the housing, eccentric straps on the eccentric sheaves, links connecting said eccentric straps to the body straps, gear wheels fast with the eccentric sheaves, and a central pinion with which said gear wheels mesh, said pinion being rotatably mounted in the housing and means for preventing rotation of the pinion.

10. In centrifugal apparatus, a number of bodies having planetary movement, seatings

for the bodies opposing their centrifugal movement, an endless loop adapted to embrace such bodies, means to deform said loop whereby the bodies are periodically retracted from the seatings and means for 20 adjusting the length of said loop.

11. In centrifugal apparatus, a number of drums or the like disposed about a main axis of rotation, a revolving housing for the drums comprising arcuate seatings and 25 straight ties connecting said seatings, and means for retracting the drums from their seatings for rotation.

In testimony whereof I affix my signature.

WILHELM MAUSS.
